Specification for Design.

Patented Oct. 29, 1912.

Application filed March 6, 1911. Serial No. 612,712. Term of patent 14 years.

To all whom it may concern:

Be it known that we, EDGAR LOWE, HOWELL WILLIAM HAFF, and WALLACE PFAU ANDRICK, all citizens of the United States, residing at Jamaica, in the county of Queens and State of New York, have invented a new, original, and ornamental Design for a Telephonic Transmitting-Station, of which the following is a specification, reference being had to the accompanying drawing.

The design relates to the form or configuration and the surface ornamentation of the instrument.

The figure is a perspective view of a station embodying the design.

The instrument is made with a paneled front having an ornamental central area with symmetrically arranged sound openings, and having a contrasting escutcheon plate beneath through which the keys project.

We claim—

The ornamental design for a telephonic transmitting station as shown and described.

EDGAR LOWE.

HOWELL WILLIAM HAFF.

WALLACE PFAU ANDRICK.
